PIVOTAL SASH AND BALANCE ASSEMBLY
Waldo O. Johnson, Wooster, Ohio, assignor to Weather-
Seal, Inc., Barberton, Ohio, a corporation of Ohio
Filed Aug. 5, 1964, Ser. No. 387,648
9 Claims. (Cl. 49—175)

The present invention relates to pivotally positioned double hung sashes and to the combination of such sashes and the balance assemblies provided therefor.

Heretofore in many different types of double hung windows, some type a balance means has been provided to facilitate easy vertical movement thereof. Also, it has been proposed heretofore to provide pivotally positioned double hung sash members that have a releasable engagement along one vertical margin of the sash with the jamb liner means provided therefor whereby the sashes can be swung inwardly about suitable vertical hinge means provided therefor to facilitate cleaning of the sashes, or for other access thereto, as desired. One of such prior constructions is shown in Harold A. Etling U.S. Patent No. 2,584,684.

The general object of the present invention is to provide a novel and improved double hung sash characterized in the improved slidable positioning of these sashes in their jamb liner means, and to the novel and improved relationship between a lock member provided on one vertical margin of the sash and its associated jamb liner means.

Another object of the invention is to provide a novel and improved relationship between a balance means used to position a sash in a jamb liner and a sash balance channel, and to provide a novel association of the balance means with the hinge means provided for a pivotally positioned sash in a window assembly.

Another object of the invention is to provide novel and improved balance means in a pivotal window sash to support such sash on both vertical margins thereof.

Another object of the invention is to provide novel and improved seal and connecting means for attaching an edge of a window sash pivotally to suitable sash positioning means.

Yet another object of the invention is to provide improved means for retaining a locking bar on a window sash in an extended operative position and to provide an improved means for retracting the locking bar to an inoperative position when it is desired to permit the window to have pivotal movement above its opposite edge.

A further object of the invention is to provide a novel and improved pivotal window that has substantially conventional balance means positioned therein and wherein the pivotal window has a good sealed engagement with its positioning means to provide an improved, attractive window assembly.

The foregoing and other objects and advantages of the invention will be made more apparent as the specification proceeds.

Attention now is particularly directed to the accompanying drawings, where:

FIG. 1 is an elevation of a novel and improved window assembly embodying the principles of the invention with portions of the window being broken away and with portions of the window assembly being shown in vertical section;

FIG. 2 is a fragmentary enlarged elevation, partially broken away and shown in vertical section, of the slide bar and associated locking means provided at the free marginal edge of the pivotally positioned window sash;

FIG. 3 is an enlarged vertical section taken on line 3—3 of FIG. 1 with both sashes moved to their lowered positions and with the pivotal action of the one window sash being indicated;

2

FIG. 4 is a vertical section through the balance means and hinge assembly used for attaching one vertical margin of a window sash to the associated window jamb as shown in FIG. 1;

5 FIG. 5 is an elevation of the hinge and balance positioning means shown in FIG. 4;

FIG. 6 is a fragmentary enlarged vertical section through the jamb liner assembly of the unit shown in FIG. 1; and

10 FIG. 7 is a fragmentary horizontal section taken on line 7—7 of FIG. 2.

In referring to corresponding members shown in the drawings and referred to in the specification, corresponding numerals are used to facilitate comparison therebetween.

15 The present invention, generally speaking, as to one important embodiment thereof, relates to the combination in a slidable and pivotal window sash assembly of a window sash, a vertically positioned jamb liner, a sash hinge balance channel slidably positioned in the jamb liner, which channel has a flat base and is of generally U-shape in horizontal section and has an offset arcuate hinge section formed thereon at its base, the channel having a pair of vertically spaced portions of its base and of the associated parts of the hinge section removed therefrom, pintle means engaging the hinge section of the sash hinge channel and of the removed parts of the channel base to secure such parts pivotally to the channel and to permit such parts to be moved to lie in the plane of the base thereof, 20 and means securing one lateral margin of the window sash to the removed channel parts for pivotal attachment to the channel, the window sash being positionable with part of the one lateral margin thereof being abutted against the base of the channel to provide a substantially sealed vertical margin on the window sash.

25 Attention now is particularly directed to the details of the structure shown in the accompanying drawings, and a novel double hung window sash assembly of the invention is indicated as a whole by the numeral 1. This sash assembly 1 is positioned in a suitable building 2 and an upper sash 3 and a lower sash 4 are vertically slidably positioned and also pivotally positioned in the sash assembly 1.

30 FIGS. 1 and 3 of the drawings best show that the building 2 may have a window frame positioned therein including a vertically extending jamb or frame member 5 which includes an inner or trim stop 6 and an outer blind stop 7 therein. A pair of vertically positioned jamb liners 8 and 9 are shown positioned on the frame member 5 and these jamb liners usually are made from a suitable metal, such as aluminum that usually is formed as an extrusion to a desired cross sectional contour to facilitate positioning of the sashes 3 and 4 therein for the desired pivotal and sliding action. The individual jamb liners 8 and 9 preferably are positioned in adjustable spaced relationship with the associated surfaces of the frame member 5 and thus usually a suitable foam plastic, or resilient member 10 is positioned under these jamb liners 8 and 9. If desired, a plurality of the foam strips may be used to space the jamb liners from the associated frame member. Usually the frame member or jamb receives some conventional type of an anchoring means, such as the unit 11 shown in FIG. 6, that engages a cap screw 12 that extends through and engages one of the jamb liners 8 or 9. The anchor unit 11 is suitably positioned in the frame member 5 so that by drawing the screw 12 into engagement therewith, the spaced relationship between the jamb liner 8 or 9 and the frame member 5 can be varied to, in turn, control or vary the lateral opening provided in the building 2 for the sash assembly 1.

35 The jamb liners 8 and 9 are restrained against undesired laterally inward movement in the window assembly

by members, such as angles or stops 13 and 14 that are secured, respectively, to the inner stop 6 and outer stop 7 of the window frame for limiting lateral inward movement of the jamb liners 8 and 9, respectively.

FIG. 3 of the drawings best shows that the jamb liners 8 and 9 are of substantially the same cross sectional contour, and with each one of these jamb liners having a recessed center section 15 and 16, respectively, provided therein, which center sections have overhanging portions of the jamb liner associated with the opening thereof to aid in forming an enclosure for receiving a portion of the sash positioning means, as hereinafter described in more detail.

The actual sash positioning means in the sash assembly 1 includes a lower sash hinge balance channel 17 and an upper hinge balance channel 18, respectively, that are slidably engaged with the jamb liners 8 and 9, respectively, for sliding vertical movement therein. Such channels 17 and 18 are actually engaged with the associated recess center sections 15 and 16 of the jamb liners by members, such as plastic end sections or runners 19 and 20.

The drawings clearly show that the hinge balance channels 17 and 18 are of generally U-shape in horizontal section and that these channels have substantially flat bases provided thereon and with each channel having an offset arcuate hinge section 21 being formed, usually, as a unitary portion of the extruded channel. The channels 17 and 18 are positioned to extend into the recessed center sections 15 and 16 of the jamb liners 8 and 9 with the open side or mouth of the channels extending into the recessed center sections of the jamb liners, and the plastic ends or runners 19 and 20 normally are attached to each end of the channels 17 and 18 by screws 17a. The runners or ends 19 and 20 are of a hollow box-shape in section with a pair of offset vertically extending edge flanges 22 and 23 being provided on each one of the runners 19 and 20. In addition, these flanges 22 and 23 each have a plurality of longitudinally extending lugs or bars 24, 25 and 26, FIG. 3, formed thereon to aid in forming guides or spacing members on the runners 19 and 20 and usually being positioned immediately adjacent the inner surfaces or faces of the recessed center sections 15 and 16 of the jamb liners. The runners 19 and 20 are snugly received in the channels 17 and 18 and usually frictionally engage therewith by means of the offset flanges 22 and 23. The runners 19 and 20 and hinge balance channels move as a unit with the upper sash or lower sash of the window assembly to aid in positioning these sashes for sliding vertical movement in the associated jamb liners 8 and 9.

As a novel and important feature of the present invention, portions of the hinge balance channels 17 and 18 are movable in relation thereto. FIGS. 4 and 5 of the drawings thus show that vertically spaced sections or portions 27 and 28 of the lower hinge balance channel 17 are suitably movable therefrom. These movable portions 27 and 28 include the associated parts of the offset hinge socket 21 formed with the base portion of the channels 17 and 18. Naturally these portions 27 and 28 movable from the channels 17 can be cut therefrom in any desired manner and usually may just be sawed therefrom during the process of manufacture of the sash assembly 1. By providing these movable portions 27 and 28, it is possible to provide a substantially sealed, and concealed hinge means for securing the lower sash 4 pivotally to the lower hinge balance channel 17. Thus, after the portions 27 and 28 are cut or otherwise made movable from the channel 17, they are re-engaged therewith preferably after a number of holes 29 are drilled therein. The movable portions 27 and 28 thus are pivotally secured to the associated channel 17 by a suitable pintle, or pintles 30 that are positioned in the offset hinge sockets 21 provided on the channel and are secured therein in a conventional manner after offset sockets 21a on the movable portions 27 and 28 of the channel have the pintle means pivotally engaged therewith. Thus, by securing the lower sash 4 to

the movable portions 27 and 28 by suitable screws 31 or the like, the lower sash 4 is adapted to be pivotally secured to this lower hinge balance channel 17 and the upper sash is similarly positioned. It will be noted that FIG. 3 of the drawings best shows that the lower sash 4 may have a rabbeted vertically extending side sash rail provided thereon and usually the movable portions 27 and 28 are secured to the laterally inner surface of this sash rail whereby that portion of the sash will be snugly and tightly associated with the lower hinge balance channel 17 and the associated or stepped portion of the sash may slidably engage and bear against associated edge portions of the jamb liner 8.

As another feature of the invention, the lower hinge balance channel 17 is shown in FIGS. 4 and 5 as having substantially conventional balance means positioned therein and adapted to aid in positioning the sash 4 for easily controlled vertical sliding action in the jamb liner 8. Thus, a conventional balance assembly 32 is positioned within the hinge balance channel 17, and has one end of the balance assembly 32 attached to a coil spring 33 by a pin 34. The opposite end of the coil spring 33 is secured in the channel 17 as by a pin 35 whereby the balance assembly is concealed within this channel 17. The balance assembly 32 includes a block and tackle means 36 that is fixedly positioned within the channel 17 and has a plurality of convolutions of a cable 37 extending to a movably positioned pulley 38 that is formed as an operative unit with the pin 34 or an end of the coil spring 33. One end of the cable 37 extends from the block and tackle means 36 and has an end member or anchor 39 secured thereto and suitably engaged with the jamb liner 8 whereby on vertical movement of the lower sash 4, the cable 37 will be pulled to extend further from the channel 17 and create tension in the coil spring 33 for retraction of the sash when moved vertically in its positioning jamb liner 8 and other associated means. While the means positioning one lateral margin of the lower sash 4 have been shown and described in detail, it will be realized that similar means are used for engaging and positioning one vertical margin of the upper sash 3 for vertical sliding movement and for pivotal action in a horizontal plane.

In order to associate the other vertical margin of the sashes 3 and 4 with slide control means and positioning means in the building 2, each of the sashes 3 and 4 has a vertically extending lock bar 40 or 41, respectively; movably associated therewith in a side sash rail thereof. Each of these lock bars 40 and 41 has a slot 42 provided therein, as shown in FIG. 2, with a portion of such slot 42 extending vertically and with an offset portion in clinched laterally outwardly and indicated at 42a also provided therein. Suitable pins, or similar members 43 extend through the slots 42 and engage the associated sash to control the position of the lock bars 40 and 41 and to permit controlled lateral extension and retraction movement of the lock bars with relation to the sash 3 in a manner similar to the constructions shown in U.S. Patent No. 2,584,684.

As a feature of the present invention, a vertically extending jamb liner 44 and 45 is provided for engaging each of the lock bars 40 and 41, respectively, for controlled sliding engagement therebetween. These jamb liners 44 and 45 preferably are made from a suitable moldable or extrudable material, usually plastic, such as polyvinyl chloride and these jamb liners have opposed sealing lips 46 and 47 formed thereon to engage, resiliently, opposite surfaces of the lock bars for sliding, substantially sealed, engagement therewith. These jamb liners 44 and 45 are positioned in suitable recesses 48 and 49 provided in a jamb 50 that is suitably attached to the building.

As a feature of the present invention, some known type of a balance means, which may be similar to the balance assembly 32, is positioned within each of the jamb liners 44 and 45 and includes a coil spring 51 that

extends downwardly therefrom. Such coil spring 51 is engaged with a balance end member 52 that is slidably positioned in the jamb liner 45, as shown in FIG. 1, and has means associated therewith for locking such balance end member 52 in a given vertical position in the window assembly. The balance end member 52 has a projection or bracket 53 suitably secured thereto and extending laterally inwardly therefrom for engaging the lower right-hand corner of the lower sash 4, as shown in the drawings, to retain the sash balance means and the sash in engagement when the sash is slidably positioned in the sash assembly. A slide catch 54 is pivotally carried by the balance end member 52 and the laterally inner surface thereof is adapted to be engaged by the laterally outer margin of the associated lock bar 41 when the sash is positioned for sliding vertical movement and this retains the slide catch in inoperative position. A spring 55 is shown compressed between the slide catch 54 and an associated portion of the balance end member to urge one end of the slide catch 54 laterally outwardly through a suitable slot 56 formed in the balance end member.

The jamb liners 44 and 45 are provided with a plurality of vertically spaced slots 57 for receiving or engaging the latch end of the slide catch 54 therin when the slide catch is free for lateral outward movement when the lock bar associated therewith is retracted. Hence, when it is desired to free one vertical margin of the lower sash 4 for pivotal movement, the upper end of the lock bar involved is forced downwardly as such upper end projects upwardly from the lower sash 4, for example, and an end of the lock bar 40 may project downwardly from the upper sash, as desired. By moving the lock bar 41 downwardly, the lock bar is pulled laterally inwardly of the sash margin and the lock bar is retracted from engagement with the jamb liner and associated slide catch. Next, upon slight controlled vertical movement of the window sash, the slide catch 54 will engage with one of the slots 57 provided in the jamb liner. Then it is only necessary to raise the sash 4 upwardly a short distance to free the bracket 53 from engagement with the sash, and the sash is free for pivotal movement about the hinge means described hereinbefore. The upper sash is freed for pivotal movement in a similar manner.

For re-engagement of the sash with the jamb liner 44 or 45 to position it for controlled vertical movement, it is only necessary to swing the sash back into the vertical plane occupied by its jamb liner and then to move the associated lock bar 40 or 41 vertically to cause the lock bar to extend to engage the slide catch 54 and move it to inoperative position. Next by action of the associated balance means, the bracket 53 will automatically be brought into engagement with the lower margin of the sash and it is positioned for controlled sliding movement in the window assembly.

Preferably each of the jamb liners 44 and 45 is spaced slightly from the bottom of the recess 48 and 49, respectively, in which it is positioned, by some strip of resilient compressible member, or means 58 or 59 and this facilitates providing space for the end of the slide catch 54 when it is locked into engagement with the associated jamb liner. Usually the balance end members 52 are of substantially U-shape in vertical section and are provided with sufficient space between the branches or legs of the U-shaped body to position the slide catch and associated means therein.

It will be realized that the plastic runners 19 and 20 and the jamb liners 44 and 45 can be made from any desired material, but preferably the use of some low friction type of plastic material is desired so that associated metal means will form low friction engagement therewith for good sliding action in the window sash assembly.

By the means used for positioning opposite vertical margins of the upper and lower sashes 3 and 4, respec-

tively, a substantially sealed, good prime window construction has been provided by the invention. At the same time, the window sashes are readily available on both surfaces thereof for cleaning or repair actions thereon, as desired. The unit when formed in quantity production can be made and assembled relatively inexpensively to provide an improved but durable window unit. Thus it is believed that the objects of the invention have been achieved.

While one complete embodiment of the invention has been disclosed herein, it will be appreciated that modification of this particular embodiment of the invention may be resorted to without departing from the scope of the invention as defined in the appended claims.

What is claimed is:

1. In a slidable and pivotal window sash assembly, the combination of,
a window sash,
a vertically positioned metal jamb liner,
a sash hinge balance channel slidably received in said jamb liner, which channel is of generally U-shape in horizontal section and has an offset arcuate hinge section formed thereon on its base, said channel having a pair of vertically spaced portions of its base and of the associated parts of said hinge section removed therefrom,
pintle means engaging said hinge section of said sash hinge balance channel and of said removed parts of said channel base to secure such parts pivotally to said sash hinge balance channel,
means securing one lateral margin of said window sash to said removed parts for pivotal attachment to sash hinge balance channel,
balance means carried by said sash hinge balance channel and having one end extending therefrom and secured to said jamb liner to support said window sash therein, and
retractable means on the other lateral margin of said window sash to position it for controlled sliding action.
2. In a slidable and pivotal window sash assembly, the combination of,
a window sash,
a vertically positioned metal jamb liner,
a sash hinge balance channel slidably received in said jamb liner, which channel is of generally U-shape in horizontal section and has an offset arcuate hinge section formed thereon on its base, said channel having a pair of vertically spaced portions of its base and of the associate parts of said hinge section removed therefrom,
pintle means engaging said hinge section of said sash hinge balance channel and of said removed parts of said channel base to secure such parts pivotally to said sash hinge balance channel,
means securing one lateral margin of said window sash to said removed parts for pivotal attachment to said sash hinge balance channel, and
balance means carried by said sash hinge balance channel and having one end extending therefrom and secured to said jamb liner to support said window sash therein.
3. In a slidable and pivotal window sash assembly, the combination of,
a window sash,
a vertically positioned jamb liner,
a sash hinge balance channel slidably positioned in said jamb liner, which channel has a flat base and is of generally U-shape in horizontal section and has an offset arcuate hinge section formed thereon at its base, said channel having a pair of vertically spaced portions of its base and of the associate parts of said hinge section removed therefrom,
pintle means engaging said hinge section of said sash hinge balance channel and of said removed parts of

said channel base to secure such parts pivotally to said sash hinge balance channel and to permit such parts to be moved to lie in the plane of said base, and means securing one lateral margin of said window sash to said removed parts for pivotal attachment to said sash hinge balance channel, said part of said one lateral margin abutted against said base of said channel.

4. In a slidable and pivotal window sash assembly, the combination of,

a window sash,
means engaging one lateral margin of said sash for pivotal and sliding movement thereof,

a lock bar slidably carried by said sash at the other lateral margin thereof for limited vertical and lateral movement with relation to said sash to extend laterally therefrom and to be retracted to a position at least substantially within said sash,

a plastic vertically extending jamb liner of substantially U-shape in section for engaging said other lateral margin of said sash and for receiving said lock bar when extended to form a substantially sealed connection therewith,

a sash balance operatively positioned in said jamb liner,

a balance end member slidably positioned in said jamb liner and engaging an end of said sash balance, means carried by said balance end member to engage the lower edge of said sash to support it on said sash balance, and

a slide catch pivotally carried by said balance end member and resiliently urged laterally outwardly thereof.

5. In a slidable and pivotal window sash assembly, the combination of,

a window sash,
means engaging one lateral margin of said sash for pivotal and sliding movement thereof,

a lock bar slidably carried by said sash at the other lateral margin thereof for limited lateral movement with relation to said sash to extend laterally therefrom and to be retracted to a position at least substantially within said sash,

a vertically extending jamb liner for engaging said other lateral margin of said sash and for receiving said lock bar when extended to form a sliding connection therewith,

a sash balance operatively associated with said jamb liner,

a balance end member slidably positioned in said jamb liner and engaging an end of said sash balance,

means carried by said balance end member to engage said sash to support it on said sash balance, and

a slide catch pivotally carried by said balance end member and resiliently urged laterally outwardly thereof.

6. In a slidable and pivotal window sash assembly, the combination of,

a window sash,

a vertically positioned metal jamb liner,
a sash hinge balance channel slidably received in said jamb liner, which channel is of generally U-shape in horizontal section and has an offset arcuate hinge section formed thereon at its base, said channel having a pair of vertically spaced portions of its base and of the associate parts of said hinge section movable therefrom,

pintle means engaging said hinge section of said sash hinge balance channel and of said movable parts of said channel base to secure such parts pivotally to said sash hinge balance channel,

means securing one lateral margin of said window sash to said movable parts for pivotal attachment to said sash hinge balance channel,

a lock bar slidably carried by said sash at the other lateral margin thereof for limited vertical and lateral

5

movement with relation to said sash to extend laterally therefrom and to be retracted to a position at least substantially within said sash,

a plastic vertically extending jamb liner of substantially U-shape in section for engaging said other lateral margin of said sash and for receiving said lock bar when extended to form a substantially sealed connection therewith,

a sash balance operatively positioned in said plastic jamb liner,

a balance end member slidably positioned in said jamb liner and engaging an end of said sash balance, means carried by said balance end member to engage the lower edge of said sash to support it on said sash balance,

a slide catch pivotally carried by said balance end member and resiliently urged laterally outwardly thereof,

said lock bar when extended engaging said slide catch to retain it in inoperative position, and said plastic jamb liner having a plurality of vertically spaced slots therein for receiving said slide catch to retain said balance end member in or about at a given vertical position when said slide catch is released by retraction of said lock bar.

20

7. In a slidable and pivotal window sash assembly, the combination of,

a window sash,

a vertically positioned jamb liner,

a sash hinge channel slidably received in said jamb liner, which channel is of generally U-shape in horizontal section and has an offset arcuate hinge section formed thereon at its base, said channel having a pair of vertically spaced portions of its base and of the associate parts of said hinge section movable therefrom,

pintle means engaging said hinge section of said sash hinge channel and of said movable parts of said channel base to secure such parts pivotally of said sash hinge channel,

means securing one lateral margin of said window sash to said movable parts for pivotal attachment to said sash hinge channel,

a lock bar slidably carried by said sash at the other lateral margin thereof for limited lateral movement with relation to said sash to extend laterally therefrom and to be retracted to a position at least substantially within said sash,

a plastic vertically extending jamb liner of substantially U-shape in section for engaging said other lateral margin of said sash and for receiving said lock bar when extended to form a substantially sealed connection therewith,

a sash balance operatively associated with said plastic jamb liner,

a balance end member, engaging an end of said sash balance, slidably positioned in said jamb liner and being engageable with said sash to support it on said sash balance,

a slide catch pivotally carried by said balance end member and being urged laterally outwardly thereof, said slide catch having an inoperative position, and said plastic jamb liner having a plurality of vertically spaced apertures therein for receiving said slide catch to retain said balance end member at a given vertical position.

40

8. In a slidable and pivotal window sash assembly, the combination of,

a window sash,

means engaging one lateral margin of said sash for pivotal and sliding movement thereof,

a lock bar slidably carried by said sash at the other lateral margin thereof for limited movement with relation to said sash to extend laterally therefrom and

50

- to be retracted to a position at least substantially within said sash,
- a plastic vertically extending jamb liner of substantially U-shape in section for engaging said other lateral margin of said sash and for receiving said lock bar when extended to form a substantially sealed connection therewith, 5
- a sash balance operatively associated with said jamb liner,
- a balance end member slidably carried by said jamb liner and engaging an end of said sash balance, 10
- means carried by said balance end member to engage said sash to support it on said sash balance,
- a slide catch pivotally carried by said balance end member and urged laterally outwardly thereof, said slide catch having an inoperative position, and 15
- said jamb liner having a plurality of vertically spaced means for engaging said slide catch to retain said balance end member at a given vertical position.
9. In a slidable and pivotal window sash assembly, the 20 combination of,
- a window sash,
- a vertically positioned metal jamb liner,
- a sash hinge balance channel slidably received in said jamb liner, which channel is of generally U-shape in 25 horizontal section and has an offset arcuate hinge section formed thereon at its base, said channel having a pair of vertically spaced portions of its base and of the associated parts of said hinge section removed therefrom,
- 30
- pintle means engaging said hinge section of said sash hinge balance channel and of said removed parts of said channel base to secure such parts pivotally to said sash hinge balance channel,
- means securing one lateral margin of said window sash 35 to said removed parts for pivotal attachment to said sash hinge balance channel,

- a lock bar slidably carried by said sash at the other lateral margin thereof for limited vertical and lateral movement with relation to said sash to extend laterally therefrom and to be retracted to a position at least substantially within said sash,
- a plastic vertically extending jamb liner of substantially U-shape in section for engaging said other lateral margin of said sash and for receiving said lock bar when extended to form a substantially sealed connection therewith,
- a sash balance operatively positioned in said plastic jamb liner,
- a balance end member slidably positioned in said jamb liner and engaging an end of said sash balance, means carried by said balance end member to engage the lower edge of said sash to support it on said sash balance,
- a slide catch pivotally carried by said balance end member and resiliently urged laterally outwardly thereof, said lock bar when extended engaging said slide catch to retain it in inoperative position, and
- said plastic jamb liner having a plurality of vertically spaced slots therein for receiving said slide catch to retain said balance end members in or about at a given vertical position when said slide catch is released by retraction of said lock bar.
